2 Sheets-Sheet 2

UNITED STATES PATENT OFFICE.

WILLIAM A. TEBO, OF ANTHONY, RHODE ISLAND, ASSIGNOR TO DRAPER CORPORATION, OF HOPEDALE, MASSACHUSETTS, A CORPORATION OF MAINE.

FILLING-THREAD-TENSIONING MECHANISM.

Application filed September 11, 1928. Serial No. 305,240.

This invention relates to filling thread tensioning mechanisms for looms and is more particularly directed to such tensioning mechanisms adapted for employment on filling replenishing looms.

Filling replenishing looms as now ordinarily constructed are provided with replenishing mechanism which, upon substantial exhaustion of filling in the shuttle, is set in operation to replenish the filling in the shuttle. The filled carriers or bobbins are ordinarily contained in a hopper and the filling end leading from the filling carriers or bobbins is secured to a fixed part so that when the shuttle is picked following replenishment, the filling will be laid in the shed and the shuttle become partially threaded. In weaving with certain kinds or characters of filling, especially of the kinky type, it is desirable that tension be placed upon the filling thread on the first pick of the shuttle, that it may not produce a defect in the resulting cloth.

An important feature of the present invention consists in a thread tensioning mechanism outside of the shuttle which may act upon the thread between the boxed shuttle and the warp threads at one side of the loom to insure that the first pick of filling laid in the shed shall be straight and under tension. In accordance with the present invention, the thread tensioning means comprises a thread clamp which, on call for replenishment of filling, is brought into action to clamp the thread at the non-replenishing side of the loom between the boxed shuttle and the warp threads, and a thread deflector between the thread clamp and the warp threads for forming a bend or bight in the thread as the lay moves forwardly following replenishment.

More specifically stated, the present invention provides a clamp between the members of which the thread extending from the shuttle into the shed is held, to thereby prevent the bending or bight-forming device from withdrawing the thread from the shuttle and confining its thread tensioning effort upon the thread leading to the opposite cloth selvage. The thread deflector is provided with a loop through which the shuttle passes as it enters the non-replenishing box, and the front portions of the loop have inclined legs over

and under which the thread is formed into a bight or bend by the forward movement of the lay.

Since the main purpose of the invention is to insure that the first and a few subsequent picks of the thread may be laid in the shed under tension following replenishment, means are provided for normally maintaining the thread clamp and thread deflector in inoperative position and on call for replenishment of filling to move the thread clamp and thread deflector to operative position, and after acting the desired number of times upon the filling thread, to again move the thread clamp and thread deflector to inoperative position.

The invention and novel features thereof will best be made clear from the following description and the accompanying drawings of one good form thereof.

In the drawings:

Fig. 1 is a perspective view of sufficient portions of a filling replenishing loom provided with the present invention to make clear the construction and operation thereof;

Fig. 2 is a cross-section through the lay when the latter is in its forward position and the filling thread has been clamped and bent about the legs of the thread deflector;

Fig. 3 is a detail in perspective showing the relative position of the filling thread and the legs of the thread deflector when the thread is in tensioned position;

Fig. 4 is a side elevation of a trip device for normally maintaining the thread clamp and thread deflector in inoperative position and freeing them for movement to operative position on call for replenishment of filling, some of the parts being shown in section; and

Fig. 5 is a detail showing part of the trip device.

The present invention will be described in connection with a filling replenishing loom having a feeler mechanism at the non-replenishing side and a replenishing mechanism or transerrer at the replenishing side of the loom. The details of the replenishing mechanism and transerrer form no essential part of the present invention and as such details are now well-known and understood, any illustration and description thereof appear unnecessary.

The loom frame may be of usual construction and is provided with the usual breast beam 1 and shipper stand 2 on which may be supported a feeler mechanism comprising a feeler stand 3 and a feeler 4 which on each detecting beat of the lay will enter the shuttle as usual to detect the condition of the filling therein. Since the feeler mechanism may be of any usual character, its details are not of importance, but the character of feeler mechanism as generally indicated in Fig. 1 may be of the type shown and described in the Brown and Repass Patent, No. 1,593,426, dated July 29, 1926.

15 Extending transversely of the loom is the transverse or rock shaft 5 which may be supported in suitable bearings 6 extending from the breast beam, and rising from the transverse or rock shaft 5 is an arm 7 to which is
20 pivotally connected at 8 an actuator 9, the rear end portion of which is provided with a finger 10 adapted to be engaged by an operator 11 when the finger 10 is operatively positioned relative thereto. The operating mem-
25 ber 11 may be the cam follower or a part connected thereto, as usual. Extending between the finger 10 and the feeler mechanism is the transmitter 12 having one end connected at 13 to a bell crank lever 14, one arm 15 of which
30 underlies the finger 10 which is pivoted at 16 to the actuator, the construction being such that should the feeler indicate substantial exhaustion of filling, the finger 10 will be operatively positioned relative to the operating mem-
35 ber 11 and effect rocking movement of the transverse or rock shaft 5 to thereby initiate replenishment of filling.

The lay 17 is provided with the usual shuttle boxes, only part of one of which is illustrated, as at 18, and the front wall of the shuttle box 18 and of the shuttle 19 is provided with an opening, as usual in this type of looms, for the entrance of the feeler 4 to feel for the filling. The lay 17 is also provided with the usual reed 20 through which extend the warp threads *a* and the cloth *b* is taken up as woven by any usual character of take-up mechanism, which is typified in the present instance by a roller 21, Fig. 2.

50 Mounted on the lay between the shuttle box 18 and the reed 20 is a plate 22 having a slot 23 through which the loop portion of the thread deflector continually extends during the weaving operation, as will be more fully
55 described, and at one side of the slot 23 the plate 22 has a thread clamping member 24, which in cooperation with another clamping member to be described serves to clamp and hold the thread *c* between the shuttle and the
60 warp threads *a* as the lay beats up following replenishment.

The cooperating clamping member comprises a plate or support 25 which is mounted upon an arm 26 extending frontwardly and held by a socketed clamp 27 upon the upright

arm 28 which is itself supported at the front of the loom, as will more fully hereinafter appear.

Mounted upon the support 25 is a plate spring 29 between which and the clamping member 24 the thread *c* is clamped and held as the lay beats up following replenishment. 70

The thread deflector has a loop portion 30 which normally extends through the slot 23 of the plate 22, and the forward extension of the thread deflector forming the loop consists of the two leg portions 31 and 32 which are inclined toward each other and cross at the point 33 slightly forward of the clamping spring 29. The leg portion 32 of the thread deflector extends forwardly and is held in a socketed fitting 34 which is itself supported by an arm 35 extending downwardly and forwardly, as will presently be explained. In order that the arms 28 and 35 which support the thread clamp and thread deflector may be held in their associated relation, a guide 36 is provided, having slots 37 and 38 in which the arms 28 and 35 are guided in their movements toward and from operative position. 90

The lay 17 may appropriately be provided with an opening 39 through which the lower leg 31 of the thread deflector may extend in non-interfering relation with the shuttle as it is picked.

From the construction described it will be apparent that the thread deflector has a looped portion which extends across the shuttle race and through which the shuttle may pass as it is picked from the replenishing side of the loom to lay the filling thread *c* within the loop of the thread deflector, as indicated in Fig. 1. When the thread clamp 29 and the thread deflector are in operative positions, as indicated in Fig. 2, and the lay beats up, the filling thread *c* will be moved frontwardly towards the fell of the cloth and finally be clamped and held between the clamping members 24 and 29 at a point between the end of the boxed shuttle and the warp threads, and since it is desirable to have the thread clamped before the thread deflector operates to form a bend or bight in the thread to take up slack extending to the opposite cloth selvage, the crossing point 33 of the leg portions 31 and 32 of the thread deflector is slightly forward of the front thread clamping member, with the result that the thread will first be clamped between the end of the shuttle and the warp threads and by continued forward movement of the lay the filling thread will be bent over and under the legs 31 and 32 of the thread deflector, substantially as indicated in Fig. 3, thereby drawing upon the thread extending to the opposite selvage, and preventing withdrawal of thread from the shuttle itself.

The bend or bight formation in the filling thread *c* which is formed as the lay moves frontwardly is well illustrated in Fig. 3 130

wherein it will be noted that the thread *c* has been moved frontwardly by the reed past the crossing point 33 of the legs 31 and 32 of the thread deflector, with the result that 5 the thread *c* will be bent under the leg 32, as at 40, and over the leg 31, as at 41, to thereby take up any slack existing in the filling thread extending to the opposite selvage. Inasmuch, however, as the slack in the 10 filling thread *c* may vary from time to time, the legs 31 and 32 of the thread deflector are made resilient to accommodate for variation in the amount of filling thread.

Since the functions of the thread clamp 15 and thread deflector are to be exercised only periodically and preferably on the first and two or three succeeding picks of the shuttle following replenishment, means are provided for normally holding the thread clamp and 20 thread deflector in an inoperative position during normal weaving and to release them for movement to operative position only on call for replenishment of filling as dictated by the feeler. To this end the thread clamp 25 29 and the thread deflector are under the control of a trip device which normally acts to maintain them in an inoperative frontward position.

The trip device is mounted upon an arm 30 42 which supports a box-like casing 43 below the breast beam, as more clearly illustrated in Figs. 1 and 2, and the details thereof are best illustrated by Figs. 4 and 5.

Pivotedly mounted in the casing 43 at 44 35 is the trip arm 45, the upper end portion of which is rounded, as at 46, and pivotally connected to the trip arm 45 at 47 is the front end portion 48 of the arm 35 carrying the thread deflector. The thread clamp carrying arm 28 is provided with a slotted portion 49 which engages a stud or screw 50 extending from the opposite side of the trip arm 45, and a spring 51 having one end connected to a pin 52 extending from the front end portion 40 of the arm 28, and its opposite end connected to a pin 53 mounted upon a bracket 54 adjustably secured to the casing 43, serves with a normal tendency to move the clamp carrying arm 28 rearwardly. Each of the arms 28 and 35 may be conveniently passed 45 through guide sleeves 55 and 56 supported upon the bracket 54 or other convenient fixed part, thereby serving to further guide the clamp carrying and thread deflector carrying arms in their movement towards and from the front of the loom.

As indicated in Fig. 4, the trip arm 45 has pivoted thereto at 57 the lever 58, the rear end portion of which is provided with a cam device or inclined member 59, and acting upon the lever 58 is a spring 60 one end of 50 which is connected to the front end portion 61 of the lever 58 and the other end at 62 to the casing 43, the tendency of the spring acting to hold the inclined end portion 59 lifted

and also tending by reason of its inclined stress to move the trip arm 45 frontwardly into the position indicated in Fig. 1.

Rotatably mounted upon the casing 43 at 63 is the ratchet and stop member or wheel 64 which is normally under the influence of a spring 65 tending to turn the ratchet member in a clockwise direction, viewing Fig. 4, and extending from the ratchet member is a stop 66. The ratchet member is provided with a series of teeth 67 and 68, the former of which are adapted to be engaged by a pawl 69 pivotally mounted at 70 upon the lever 58 and having at its upper end a projection 71 adapted to be engaged by the trip arm 45 when the latter is moved rearwardly, as will presently be described, to thereby trip the pawl 69 from engagement with the ratchet teeth 67. Obviously, when the pawl 69 is disengaged from the teeth 67 the spring 65 will turn the ratchet wheel in a clockwise direction.

Pivotally associated with the trip arm 45 is a holding pawl 72 the end of which is adapted to engage the teeth 68 of the ratchet wheel and hold it from rotative movement 90 clockwise, viewing Fig. 4, and a spring 73 extends between the pawls 69 and 72 and acts normally to hold them in operative relation with their respective ratchet teeth.

The lower portion of the trip arm 45 has 95 the arm 74 extending therefrom alongside of the ratchet 72, which latter is provided with a disengaging projection 75 underlying the arm 74, the result being that when the trip arm 45 is moved rearwardly, as indicated in 100 Fig. 4, the arm 74 will disengage the holding pawl 72 from the ratchet teeth 68 and permit the ratchet wheel 64 to rotate under the action of the spring 65 until the stop 66 engages the end of the holding pawl 72 to 105 thereby limit the rotative movement of the ratchet wheel in a clockwise direction.

Secured to the ratchet wheel 64 and rotatable therewith is the cam or arm stop 76 having a slabbed-off portion 77, the construction being such that when the trip arm 45 is moved to its backward position, as indicated in Fig. 4, and the holding pawl 72 has been tripped, the circular portion of the cam 76 will be brought into position above the 110 arm 74 to thereby hold the arm 74 and 115 force the trip arm 45 in its rearward position, but when the actuating pawl 69 operates upon its ratchet teeth 67 to turn the ratchet wheel in a contraclockwise direction, Fig. 4, 120 the slabbed-off portion 77 of the cam 76 will finally be stepped along by the ratchet 69 until it comes above the end of the arm 74, whereupon the spring 60 will act to move the trip arm 45 frontwardly into its inoperative 125 position. As before noted, the holding pawl 72 acts upon the teeth 68 to hold the ratchet wheel from rotation in a clockwise direction, Fig. 4, when the trip arm 45 is in its front position and the slabbed-off portion 77 of the 130

cam 76 has permitted such movement of the trip arm. This position of the trip arm 45, indicated in Fig. 1, will be maintained by the holding pawl 72 during normal weaving operations.

Mounted upon the transverse or rock shaft 5 is an arm 78 having a roller 79 adapted to ride up the inclined surface of the trip arm 45 when the transverse or rock shaft is turned 10 responsive to a call for replenishment of filling and thereby cause the trip arm 45 to be swung about its pivotal mounting 44 into its rearward position, as indicated in Fig. 4, and since the projection 71 of the actuating pawl 15 69 and the projection 75 of the holding pawl 72 are then engaged by the trip arm and its projection 74 respectively, the ratchet wheel 64 will turn clockwise to bring the circular portion of the cam 76 above the projecting 20 arm 74, thereby holding the trip arm in its rearward position. The movement of the trip arm 45 by the roller 79 is slightly greater than the rearward position of the trip arm 45, so that when the roller 79 releases the trip 25 arm it will swing slightly about its pivotal mounting 44 under the action of the spring 60 to thereby permit the actuating pawl 69 to engage its cooperating teeth 67 of the ratchet wheel, and the holding pawl 72 to 30 engage its ratchet teeth 68. If, now, the lever 58 be rocked upon its pivotal support 57, the actuating pawl 69 will act upon its ratchet teeth 67 to turn the ratchet wheel in a contraclockwise direction, while the holding pawl 72 will hold the ratchet wheel into the 35 position so moved.

Mounted upon the lay is a downwardly extending arm 80, Fig. 1, from the lower end of which extends an adjustable slide 81 having a roller 82, which on each forward movement of the lay rides up the incline 59 of the lever 58 and rocks the lever about its pivotal support 57, with the result that the ratchet wheel will be turned step-by-step on each 40 frontward movement of the lay until the slabbed-off portion 77 of the cam 76 permits the trip arm 45 to be moved frontwardly under the stress of the spring 60, and since the lever 58 is pivoted to the trip arm 45 it will 45 be withdrawn frontwardly out of further engagement with the trip actuator or roller 82 mounted on the lay and the parts, including the clamping member 29 and the thread deflector will be moved frontwardly to an in- 50 operative position and there held until another call for replenishment of filling.

From the construction described as one good practical form of the present invention it will be noted that the invention provides a 60 thread clamp to clamp the filling thread between the end of the boxed shuttle and the warp threads on beat-up movement of the lay following replenishment, and as the lay beats up and after the thread has been clamped, 65 the lay will move the filling thread further

frontward to cause it to be deflected or bent by the inclined leg portions of the thread deflector at a point between the thread clamp and the warp threads. It will also be seen that the invention provides means acting 70 during normal weaving operation to maintain the thread clamp and thread deflector in an inoperative position, and that upon call for replenishment of filling as dictated by the 75 feeler the thread clamp and thread deflector will be moved to their rearward operative position and maintained in such position for a number of picks depending upon the number of teeth provided on the ratchet wheel 64 or as directed by the trip device. 80

What is claimed is:

1. In a loom, the combination of the lay and shuttle boxes, a filling thread tensioning device constructed and arranged to act upon the filling thread between the boxed shuttle and cloth selvage and comprising thread clamping members between which the shuttle passes for clamping the filling thread as the lay beats up, and a thread deflector between the clamp and cloth selvage having relatively inclined members between which the filling is laid by the shuttle for producing a bend or bight in the thread after it has been clamped and as it is moved frontwardly on beat up movement of the lay. 95

2. In a loom, the combination of the lay and shuttle boxes, a filling thread tensioning device between the shuttle box and the cloth selvage, comprising a thread clamp having clamping members between which the shuttle passes to clamp the thread adjacent the inner end of the shuttle box as the lay beats up, and a thread deflector between the clamp and cloth selvage having inclined intersecting legs which engage the thread as it is moved frontwardly by the lay for producing a bend or bight in the thread extending from the clamp to the remote cloth selvage. 105

3. In a loom, the combination of the lay and shuttle boxes, a filling thread tensioning device between the shuttle box and the edge of the cloth, including a clamp to clamp the thread adjacent the inner end of the shuttle box, and a thread deflector comprising crossing leg portions over and under which the filling thread is bent at a point between the clamp and warp threads. 115

4. In a loom, the combination of the lay and shuttle boxes, a filling thread tensioning device between the shuttle box and the edge of the cloth, including a clamp to clamp the thread adjacent the inner end of the shuttle box, and a thread deflector having a loop through which the shuttle passes and leg portions over and under which the thread is bent 120 at a point between the clamp and warp threads. 125

5. In a loom, the combination of the lay and shuttle boxes, a filling thread tensioning device between the shuttle box and the edge 130

- of the cloth, including a clamp to clamp the thread adjacent the inner end of the shuttle box, and a thread deflector having a loop through which the shuttle passes and front-
5 wardly extending leg portions over and under which the thread is bent at a point be-
tween the clamp and warp threads as the lay moves frontwardly. 70
6. In a loom, the combination of the lay and shuttle boxes, a filling thread tension-
10 ing device between the shuttle box and the edge of the cloth, including a clamp to clamp the thread adjacent the inner end of the shuttle box, and a thread deflector having upper
15 and lower portions forming a loop through which the shuttle passes and frontwardly ex-
tending yielding leg portions about which the filling thread is bent at a point between
20 the clamp and warp threads as the lay moves frontwardly. 75
7. In a loom, the combination of the lay and shuttle boxes, a thread clamping plate carried by the lay, a clamping member front-
25 ward of the lay to cooperate with the clamp-
ing plate to clamp the filling thread between
30 the inner end of the boxed shuttle and warp
threads as the lay moves frontwardly, and a
35 thread deflector having a loop through which
the shuttle passes and frontwardly extend-
40 ing leg portions between the thread clamp
and warp threads about which the filling
45 thread is bent as the lay moves frontwardly. 80
8. In a loom, the combination of the lay and shuttle boxes, a thread clamping plate carried by the lay, a clamping member front-
25 ward of the lay to cooperate with the clamp-
ing plate to clamp the filling thread between
30 the inner end of the boxed shuttle and warp
threads as the lay moves frontwardly, and a
35 thread deflector having a loop through which
the shuttle passes and frontwardly extending
40 and crossing leg portions between the thread
clamp and warp threads about which the fill-
45 ing thread is bent as the lay moves front-
wardly. 85
9. In a loom, the combination of the lay and shuttle boxes, a filling thread tensioning device between the boxed shuttle and warp threads, comprising cooperating clamping
50 members one on the lay and the other front-
ward thereof adjacent the inner end of the boxed shuttle, and a thread deflector having inclined crossing leg portions between which the thread is laid by the shuttle and about
55 which it is caused to be bent as the lay moves frontwardly. 90
10. In a loom, the combination of the lay and shuttle boxes, a filling thread tensioning device between the boxed shuttle and warp threads, comprising cooperating clamp-
60 ing members one on the lay and the other front-
ward thereof adjacent the inner end of the boxed shuttle, and a thread deflector having inclined crossing leg portions between
65 which the thread is laid by the shuttle and
about which it is caused to be bent as the lay moves frontwardly, the crossing of the inclined leg portions of the thread deflector being positioned frontward of the thread clamp to insure that the thread shall be first 70
- about which it is caused to be bent as the lay moves frontwardly, the crossing of the inclined leg portions of the thread deflector being positioned frontward of the thread clamp to insure that the thread shall be first 70
11. In a loom, the combination of the lay and shuttle boxes, a filling thread tensioning device to act upon the thread between the boxed shuttle and warp threads comprising a clamp for clamping the thread adjacent the inner end of the boxed shuttle, and a thread deflector between the clamp and warp threads, means normally effective for main-
75 taining the thread deflector and a member of the clamp in inoperative position, and means for periodically moving the thread deflector and clamp member into operative position. 80
12. In a loom, the combination of the lay and shuttle boxes, a filling thread tensioning device to act upon the thread between the boxed shuttle and warp threads comprising a clamp for clamping the thread adjacent the inner end of the boxed shuttle, and a thread deflector between the clamp and warp threads, 85 means normally effective for maintaining the thread deflector and a member of the clamp in inoperative position, means for periodically moving the thread deflector and clamp mem-
90 ber into operative position, and means for again moving the thread deflector and clamp member to inoperative position after the thread has been clamped and tensioned. 95
13. In a loom, the combination of the lay and shuttle boxes, a filling thread tensioning device to act upon the thread between the boxed shuttle and warp threads comprising a clamp for clamping the thread adjacent the inner end of the boxed shuttle, and a thread deflector between the clamp and warp threads having inclined crossing members about 100 which the thread may be bent as the lay moves frontwardly, means normally effective for maintaining the thread deflector and a mem-
105 ber of the clamp in inoperative position, and means for periodically moving the thread de-
flector and clamp member into operative position. 110
14. In a filling replenishing loom, the combination of the lay and shuttle boxes, a thread tensioning device to act upon the thread be-
115 tween the boxed shuttle and warp threads comprising a thread clamp and a thread de-
flector to form a bend or bight in the thread between the thread clamp and warp threads, 120 means normally acting to maintain the clamp and deflector inoperative, a filling feeler, and means rendered operative by the filling feeler on detection of substantial exhaustion of fill-
125 ing to cause the clamp and thread deflector to become operative that the first pick of filling following replenishment may be tensioned. 130
15. In a filling replenishing loom, the combination of the lay and shuttle boxes, a thread tensioning device to act upon the thread be-

- 5 tween the boxed shuttle and warp threads comprising a thread clamp and a thread deflector to form a bend or bight in the thread between the thread clamp and warp threads, 5 means normally acting to maintain the clamp and deflector inoperative, a filling feeler, means rendered operative by the filling feeler on detection of substantial exhaustion of filling to cause the clamp and thread deflector to 10 become operative that the first pick of filling following replenishment may be tensioned, and means actuated by the lay for returning the clamp and thread deflector to inoperative position.
- 15 16. In a filling replenishing loom, the combination of the lay and shuttle boxes, a thread tensioning device to act upon the thread between the boxed shuttle and warp threads comprising a thread clamp and a thread de- 20 flector to form a bend or bight in the thread between the thread clamp and warp threads, a trip device normally acting to maintain the clamp and thread deflector inoperative, a filling feeler to detect the condition of the filling 25 in the shuttle on detecting beats, a transverse or rock shaft actuated on call for replenishment of filling, and means operated by the rock shaft to free the clamp and thread deflector for movement to operative position to 30 tension the first pick of filling following re- plenishment.

17. In a filling replenishing loom, the combination of the lay and shuttle boxes, a thread tensioning device to act upon the thread be- 35 tween the boxed shuttle and warp threads comprising a thread clamp and a thread deflector to form a bend or bight in the thread between the thread clamp and warp threads, a trip device normally acting to maintain the clamp and thread deflector inoperative, a 40 filling feeler to detect the condition of the filling in the shuttle on detecting beats, a transverse or rock shaft actuated on call for replenishment of filling, means operated by the rock shaft to free the clamp and thread 45 deflector for movement to operative position to tension the first pick of filling following re- plenishment, and means actuated by the lay to return the clamp and thread deflector to 50 inoperative position.

18. A thread tensioning device for looms, comprising a clamp to clamp the thread be- 55 tween the boxed shuttle and warp threads, and a thread deflector between the clamp and warp threads having a loop through which the filling thread is laid by the shuttle, and inclined crossing legs about which the clamped thread is bent on frontward move- ment of the lay.

In testimony whereof, I have signed my 60 name to this specification.

WILLIAM A. TEBO.
